APPARATUS FOR CUTTING FIBERS

Robert C. Wilkie, Andover, Mass., assignor to
Pacific Mills, Lawrence, Mass., a corporation of
Massachusetts

Application April 27, 1948, Serial No. 23,585

3 Claims. (Cl. 164—61)

1

My invention relates to an apparatus for cutting fibers to variable lengths. An object is to impart a sidewise reciprocating movement to a sheet of moving fibers in order to deliver the fiber sheet at varying angles to a pair of cutting rolls so that such rolls may cut or fracture the fibers into varying lengths. Such a pair of cutting rolls is shown and described in my Patents No. 2,438,469, issued March 23, 1948. Another object is to form large bundles of fibers into an even sheet which can then be reciprocated sidewise.

In the drawing Fig. 1 is a longitudinal elevation partly in section of my apparatus, Fig. 2 is a vertical view on the line 2—2 of Fig. 1, Fig. 3 is a vertical section on line 3—3 of Fig. 2, Fig. 4 is a side view of the roll 61, Fig. 5 illustrates the means for reciprocating the bar 7, and Fig. 6 is a diagram illustrating the variable lengths of the cut fibers.

The strands of bundles of fibers are drawn from coils in boxes 60, or other packing means, over guide rollers and over a stationary roll 61 having upwardly projecting pins 62 which arrange the strands side by side in a sheet C. The sheet passes through a tensioning device consisting of rolls 4 and 5 journaled in slotted arms 6 adjustably secured to the frame of the machine by bolts. The sheet passes over a tiltable roll 8 mounted in a pivoted and rocking frame 15 and thence between delivery rolls 44, 46 and 48 to the fracturing or cutting rolls 10, 12 described in my Patent No. 2,438,469. The upper roll 10 has on its surface a number of helical threads which cut or fracture the fiber against the lower roll which has a plain surface. The threads are disposed at a wide angle, such as approximately 80°, to the axis of the roll, Fig. 6.

The frame 15 is rocked by a bar 7, Figs. 2 and 3, mounted to reciprocate in slots in vertical uprights 11 secured to the frame of the machine. The bar 7 is pivoted to a link 72 which is reciprocated by the means shown in Fig. 5. The roll 46, driven by means not shown, drives a sprocket chain 41 which drives a roll fast on a shaft on which is a worm 43. The worm drives a worm gear 45 fast on a shaft 47 having a crank 49 which is connected to the link 72, pivoted to the bar 7.

The bar 7, Fig. 3, has an angle iron 71 bolted thereto in the horizontal part of which is secured a stud 13 which passes loosely through a hole in a cross-bar 14 fastened to the frame 15 in which the roll 8, over which the sheet C of fibers passes, is journaled. Vertical studs 16

2

project upward from the lower member 9 of the frame 15 and are bolted thereto in slots so as to be adjustable sidewise thereon to confine between them the sheet of fibers. The distance between the studs is slightly less than the width of the sheet so that the sheet is maintained in substantially rectangular cross section of uniform thickness.

A bracket 17 depending from the lower member 9 of the frame carries a pin 18 which is journaled in a bracket 19 fastened to a cross bar 20 of the frame of the machine. The frame 15 and the parts carried thereby are pivoted on pin 18.

When the bar 7 is reciprocated, it rocks the frame 15 about its pivot 18 and tilts the roll 8 first one way and then the other. This causes the moving sheet of fibers to be displaced sidewise as it is presented to the feed rolls 44, 46 and 48 and to be presented to the cutting rolls 10 and 12 at varying angles whereby the lengths of the cut fibers are varied.

Fig. 6 is a diagram illustrating how a small change in the angle at which the fibers are presented to the cutting threads 100 and 101 of the roll 10 results in a comparatively large variation in the length of the cut fibers. A preferred angle at which the threads are arranged relative to the axis of the roll 10 is about 80°. The fibers, when presented to the threads at right angles to the axis of the roll on the line a—b, are cut to the length a—b. When the fibers are presented in the direction c—d, i. e. 84° to the axis, they are cut to the length c—d, and when the fibers are presented in the direction e—f, i. e. 93° to the axis they are cut to the length e—f. By suitably adjusting the throw of crank 49, Fig. 5, and thereby the magnitude of the angle through which the roll 8 is tilted and by the use of cutting rolls having cutting threads at different angles to the axis of the rolls, the desired lengths of cut fibers and the variations in their lengths may be obtained, such as 3 to 5 inches, 3 to 6 inches, 2 to 5 inches, etc.

45 I claim:

1. In an apparatus for cutting fibers to variable lengths in which a number of strands of fibers are arranged in a sheet and are cut by a pair of cutting rolls one of which has cutting threads set helically thereon, feed rolls in advance of the cutting rolls, a roll mounted in a tiltable frame, means to guide the sheet of fibers over said roll, and means to rock said frame in a vertical plane about a pivot below the axis of said roll and in a vertical plane midway between the ends

of said roll to alternately displace the sheet of fibers passing thereover both vertically and laterally whereby said sheet of fibers is moved sidewise by said roll and is delivered at varying angles to said feed rolls.

2. In an apparatus for cutting fibers to variable lengths in which a number of strands of fibers are arranged in a sheet and are cut by a pair of cutting rolls one of which has cutting threads set helically thereon, feed rolls in advance of the cutting rolls, a roll mounted in a tiltable frame, means to guide the sheet of fibers over said roll, and means to rock said frame in a vertical plane about a pivot pin below the axis of said roll and in a vertical plane midway between the ends of said roll to alternately displace the fibers of said sheet in arcs centered about said pin whereby said fibers are moved sidewise by said roll and are delivered at varying angles to said feed rolls.

3. Means in an apparatus for feeding a sheet of fibers to a pair of cutting rolls one of which has helical cutting threads set at an angle of approximately 80° to the axis of the roll, said means comprising feed rolls in advance of said cutting rolls, a frame tiltable in a vertical plane,

a roll mounted in said frame, means to feed the sheet of fibers over said roll, a horizontal pin on which said frame is pivoted below the plane of the sheet supporting surface of said roll and equidistant from the ends of said roll, and means connecting one of said feed rolls and said frame to tilt said frame in a vertical plane on said pin whereby said sheet of fibers is delivered to said feed rolls at varying angles.
